DEVICE FOR COOLING BOTTLES OR
SIMILAR VESSELS

Jacques Bienenfeld, Paris, France

Application April 8, 1933, Serial No. 665,241
In France April 16, 1932

3 Claims. (Cl. 62—76)

This invention relates to a device for cooling bottles or similar vessels. Such devices ordinarily comprise an inset which can be set into a bucket, tub or the like or made integral with the latter.

5 The bottle or like vessel is put into the opening of the inset, while the cooling ice is contained in a space between the bottle and the wall of the bucket. An essential drawback of the hitherto known coolers is that the ice space gradually fills 10 with a mixture of ice and water produced by the melting of the ice. The temperature of this mixture is the same as the temperature of the melting ice. Furthermore the use of such coolers entails a pretty high consumption of ice.

15 A first object of the invention is to avoid these inconveniences by providing a cooler which is so designed that, on the one hand, the bottle or the like is not substantially moistened with liquid and, on the other hand, the ice is constantly held 20 in a dry condition in an annular space.

Another object of the invention is to provide a cold air space beneath the bottle, said air space aiding in cooling the bottle and capable of receiving other vessels such as butter-dishes, caviar-dishes and the like.

25 Another object of the invention is to provide cooling devices through which the volume of the cold air space may be maintained substantially constant.

30 Several forms of the invention are shown in the appended drawings, in which

Figure 1 is a view in elevation showing parts in section.

Figure 2 is an enlarged sectional view of part 35 of the cooling device.

Figure 3 shows another form of the invention.

Figures 4 and 5 show still another embodiment of the invention.

30 In a bucket or tub 1 of the usual form is a bottle receiving frame (Figure 1). This frame is formed of a plurality of bars 5 which are assembled together through two rings, one at the top and the other at the bottom. The bottom 6 of the ice-container is formed of a plate provided 40 with holes 7. From the bottom 6 extend bars 8 which are assembled together in their lower part through a ring which supports the whole inset on the bottom of the cooler 1.

The annular space 10 is closed in its upper part 45 through a ring 9 provided in its centre with an opening for inserting the bottle. In its lower part the tub 1 is provided upon feet 2 with which the tub rests on a table or the like. In the outer wall of the tub 1 and at the lower end of the same, 50 at the level of the floor, there is provided a recess

11 of substantially rectangular form in its upper part, while the lower part thereof has a circular form. In said recess is received an inset 12 of the same form. In said inset 12 there is provided an elongated opening 14 in which an inset 15 of transparent material is inserted. In the embodiment according to Figures 1 and 2 said inset 15 is formed of a small glass tube projecting inwardly over the part 12 so that the water which has been produced may enter freely the lower and upper ends of the tube. In the lower part of the body 12 there is provided an opening 13. This opening is closed by a hemispherical body the surface of the section of which is adjacent to the circular surface 16 of the body 12. A stud 18 is secured to the inset 12 and passes centrally through the half ball 17 to firmly attach said ball to the inset 12. The closing body also comprises a segment-like opening 19 which can be brought to register with the opening 13 through a handle secured to the 5 10 15 closing body 17. When the quantity of water which has formed in the lower part of the tub 1 reaches such a height that the water is visible through the small tube 15, the cock 17 and the segment-like form of the openings 13 and 19 permit said water to be discharged in a very short time.

In operation ice is always present in the space 10 of the cooler. The water which has formed flows into the lower space beneath the bottom 6. 30 Because of its low temperature the ice in the annular space 10 produces an exceedingly strong cooling effect on the bottle or like vessel put into the cooler. The air between the lumps of ice in the space 10 is also very intensively cooled 35 and in consequence of this said air falls onto the bottom of the cooler 1, so that the air space beneath the bottom 6 is also maintained at a very low temperature. Thus the bottle is also intensively cooled from the bottom without permitting the bottom of the bottle to come into contact with the water, the temperature of which is lower than the temperature of the air. The space beneath the bottom 6 may be advantageously 40 used for cooling vessels containing butter, caviar and the like.

In the embodiment according to Figure 3 the annular container comprises an outer conical wall 2a adjacent to the inner face of the tub 1a. The 45 annular container also comprises an inner wall 5a of cylindrical form also consisting of a plurality of bars and a lower bottom 7a. The bars 8a of the inner wall are secured to horizontally arranged rings 6a. In a similar manner the bars 50 55

2a are maintained in assembled relation through an upper ring 3a and a lower ring 4a.

The lower ends of the bars 5a are angularly curved outwardly and form the perforated bottom of the annular container together with wires 8a resting on them.

The bars 2a project over the bottom 7a of the annular container and form feet on which the ice-container rests in the tub 1a.

10 The extensions of the outer wall 2a of the annular container projecting over the bottom of the latter may, however, be dispensed with and instead of providing them the whole container may also be inserted into the tub 1a.

15 Projecting radially from the outer walls in the middle of the same and beneath the bottom 7a of the annular container are shoulders 9a on which the surface 10a rests which is shown diagrammatically in the drawings.

20 The dimensions of the space 12a beneath the supports 9a are such that said space can contain the whole water formed by the melting of the ice contained in the annular vessel, a sufficient air space always remaining between the 25 bottom of the bottle and the surface of the water.

The upper annular surface of the annular container is also closed by a cover, not shown. In a cooler serving only for bottles said cover is made of annular form so that it covers the annular surface of the annular ice-container. However, in a cooler designed for serving, to maintain articles of food or the like in a fresh condition, a central inset will still be advantageously used in the annular cover in order to permit the central opening of the cover to be completely closed. The vessels designed for maintaining articles of food in a fresh condition may have a cylindrical form so that they may be inserted through the central opening of the annular container, said vessels being then surrounded throughout a part of their height by the ice in the annular space. However, the vessels may also be so flat that they may be received in the air space 11a beneath the annular container.

45 Since the bottles or vessels to be cooled often have different diameters and since it is desirable to bring the annular ice layer as closely as possible adjacent to the vessel to be cooled, it is advantageous to make the inner wall and the bot-

tom of the annular container of different pieces. Figures 4 and 5 show by way of example such an embodiment of the invention. The inner wall of the annular container is formed of a plurality of wall segments 5b and 5b' loosely overlapping one another and which, in this case, are not perforated. Each wall segment has a bottom part 7b and the various bottom parts also overlap one another. The bottom parts are provided with perforations. In this embodiment the bottom and the inner wall of the annular container are extensible so that the inner wall of the container may fit different diameters of the bottles or vessels. Since also in this embodiment

10 the inner wall of the container is not provided with perforations the walls of the bottle are not moistened when such a construction is used.

When making the tubs first, it is, of course, not necessary to make the tub proper and the container inset so that both form distinct parts; on 20 the contrary the inset may be made integral with the bucket proper. In this case the outer wall 2b of the annular container may be dispensed with, since the walls of the tub do its duty.

25 In order that the containers for the bottles, articles of food or the like to be cooled may be conveniently transported in coolers, the latter are preferably made portable and, for instance, provided with an ear or a handle.

30 I claim:

1. A cooling device comprising a tub, a framework carried in said tub to centrally support a bottle to be cooled, said framework thereby forming an ice chamber between the sides of the tub and the support for the bottle, means for spacing said framework from the bottom of the tub, and a perforated-bottom plate for the ice chamber, said framework being yieldable to conform closely to different size bottles.

35 2. A cooling device according to claim 1, wherein the perforated bottom is integral with the parts forming the bottle enclosing framework and therefore yieldable.

40 3. A cooling device according to claim 1, wherein the bottle supporting framework is made of overlapping strips, slideable with relation to one another to conform to different bottle sizes.

45 JACQUES BIENENFELD.
